UNITED STATES PATENT OFFICE

HARRY H. HONIGBAUM, OF NEW YORK, N. Y.

MATCH

Application filed August 21, 1929. Serial No. 387,320.

This invention is a match and more particularly a match so constituted that it will burn a relatively short time and then immediately become extinguished so that if it is discarded in inflammable material it will not remain lighted sufficiently long to cause resulting conflagration.

Matches as now generally made embody a splint which is inflammable throughout its entire length whether the splint be of wood or paper. It is of course true that under the present practice, the splints are paraffin dipped for only a portion of their length, but nevertheless as the match burns the paraffin recedes before the flame so as to cause a relatively bright and active flame until the entire splint is consumed. According to the present invention, in contra-distinction, a match is made so that when only a sufficient portion of the length thereof will burn as is required to light a cigarette, pipe or cigar, and the match may thereupon be held for a moment until it has burned itself out and then may be discarded without fear of igniting inflammable material into which it may fall. Aside from the safety feature referred to the match of this invention will not burn the fingers as the flame is extinguished long before it reaches the fingers holding the match.

In the preferred manner of making matches in accordance with this invention, the splint portion of the match is composed of an inflammable and a non-inflammable part. For example, the portion of the splint adapted to be held in the hand is preferably made of metal but some other non-inflammable material may be used, and may conveniently be in the form of a wire rod or strip of sheet metal to one end of which is affixed a paper or wooden portion which may be dipped in paraffin to render it more inflammable, and the free end of this inflammable part is adapted to provide the usual head which when struck ignites the inflammable part which burns until it is wholly consumed whereupon it becomes extinguished. The inflammable part is, however, relatively short for the reasons stated.

If desired, the non-inflammable part may

be relatively short and a so-called handle part either of inflammable or non-inflammable material may be mounted thereon in spaced relation to the inflammable portion of the match which carries the head, the spacing being sufficient to preclude communication of the flame from the inflammable part to the handle in the event that the handle is of combustible material.

Features of the invention other than those specified will be apparent from the following detailed description and the accompanying drawings, and from the appended claims.

The accompanying drawings illustrate different practical embodiments of the invention, but the constructions therein shown are to be understood as illustrative, only, and not as defining the limits of the invention.

Figure 1 is a central longitudinal section of one form of match embodying the present invention.

Figure 2 is a side elevation, of said match.

Figure 3 is a longitudinal section through a modified form of match of this invention.

Figure 4 is a side elevation of the match in Figure 3.

By reference to Figures 1 and 2 it will be noted that the splint is formed of parts 1 and 2, the latter of which is of highly inflammable material such as wood, paper, and the like, and this portion may be dipped in paraffin as is common in the match art to render it more inflammable. The part 1 may be in the form of a wire rod or a strip of sheet metal suitably secured to the part 2, as by impaling the part 2 thereon or in any other convenient way. The part 2 is headed by dipping or otherwise.

In the construction of Figure 2 the non-combustible part 1 is adapted to be grasped by the fingers while striking and holding the match and the match is adapted to be held until the part 2 is fully extinguished, it being possible to do this without burning the fingers by the flame from part 2 as part 1 is made sufficiently long to permit it to be grasped remotely with respect to part 2. In the construction of Figures 3 and 4, the match is provided with a so-called handle portion 4 connected to the inflammable part 2 by a

5 relatively short connection 1^a which may be made in the same manner as part 1 of Figures 1 and 2, and somewhat shorter. The handle 4 may be of either inflammable or non-inflammable material as may be desired, the spacing between the parts 2 and 4 being sufficient to preclude the communication of flame from the part 2 to the part 4.

10 The manner of manipulating the match in either instance is conventional except that no care need be taken against burning the fingers as the non-inflammable parts 1 and 1^a form a positive safeguard against such accident. These non-inflammable parts, moreover, permit the part 2 to be made relatively small, i. e. of just sufficient size to fulfill the normal functions of lighting a pipe, cigar, or cigarette. In practice this part burns with considerable rapidity and the head and 20 active flame well adapted for ignition purposes, and yet this flame is of such short duration that while thoroughly effective for ignition purposes, it will die out in a sufficiently short period so that even the most 25 impatient person will not hesitate to hold the match during this short interval, of this operation. Thus, when the match is discarded all combustible parts thereof have been consumed and even though it fall in 30 highly inflammable material, ignition of such material will not result.

35 The match of this invention may be economically manufactured, is thoroughly efficient for its intended purposes, and at the same time is absolutely safe both from the standpoint of personal injury and from the standpoint of inadvertent conflagration.

40 I wish it understood that while I have referred to the non-inflammable parts as preferably made of metal, these parts may be made of other non-combustible material without departing from this invention, the scope of which is to be fully understood as fully commensurate with the appended claims.

45 Having thus fully described my invention, what I claim as new and desire to secure by Letters Patent is:

50 1. A match embodying a splint comprising a fibrous (paper or wood) combustible portion, and a fibrous (paper or wood) handle in aligned spaced relation thereto, a metallic member connected at its opposite ends respectively to the handle and combustible portions, and a striking head on the free end of the 55 combustible portion.

55 2. A match embodying a fibrous (wood or paper) combustible portion having a head extending in one direction from said portion, and a metallic portion extending from said combustible portion in the opposite direction from said head.

In testimony whereof I have signed the foregoing specification.

HARRY H. HONIGBAUM.
